CLAIM

The ornamental design for a hardened skin remover, as shown and described.

DESCRIPTION

FIG. 1 is a perspective view of a hardened skin remover showing my new design;FIG. 2 is a front elevational view thereof (the rear elevational view is a mirror image);

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of an alternate embodiment of the hardened skin remover shown in FIG. 1;FIG. 8 is a front elevational view thereof (the rear eleva-

FIG. 9 is a left side elevational view thereof;

FIG. 10 is a right side elevational view thereof;

FIG. 11 is a top plan view thereof; and,

FIG. 12 is a bottom plan view thereof.
